UNITED STATES PATENT OFFICE.

ARNOLD GLADSTONE SLADDIN, OF BRIGHOUSE, ENGLAND.

PAD FOR GARMENTS.

Application filed October 12, 1928, Serial No. 141,128, and in Great Britain September 11, 1928.

This invention relates to pads for garments in which a number of layers of cotton fibres or cotton wadding or wadding in which cotton fibres predominate, (some or 5 all of which may have a film of size upon one side forming a backing), is secured together by stitching or sewing, and has for its object an improved and cheaper construction of such pads whereby the said stitching 10 or sewing is dispensed with. This is accomplished by applying a thin film of wet or liquid size to one side of certain of the layers of wadding of which the pads are composed and relatively arranging said 15 layers while the size is in a wet state, whereby the whole or a part of a wet surface of one layer is adapted to engage mainly a corresponding part of a dry surface of a contacting layer, so that, upon the superimposed layers being pressed together the 20 wet or liquid size more or less penetrates the contacting surfaces causing them to adhere together, and when dried a pad is produced of great stability adapted to be handled and stocked without losing its original 25 shape.

Hitherto, when constructing these pads, the several layers of cotton wadding or similar fibrous material cut to a desired shape 30 and of varying sizes are sandwiched between similarly shaped sheets of paper or wadding having a coat of size upon one side, forming a cover therefor, the whole being secured together by stitching more or less around the 35 edges and across the pad itself, which gives the pad a more or less quilted appearance more pronounced in some cases than in others according to the thickness of the pad. Pads of this construction, it is found, possess 40 certain disadvantages, inasmuch, when pressing the garment the uneven surface of the pad occasioned by the aforesaid stitching is often reflected upon the surface of the garment at this part, sometimes, where thin cloths are used, setting off the aforesaid 45 stitches thereon so as to be noticeable. In the use of the improved pad before-mentioned this is impossible because a uniform plain surface obtains throughout consequently the pad may be used with the greatest 50 advantage to the garment.

In constructing the improved pad two pieces of cotton wadding having a thin film of dry size upon one side are cut from a 55 sheet of this material in the well known manner. These cuttings are adapted to

form a cover for the pad and may be of equal size and shape, or one may be slightly less than the other where a pad is required having a thin or feathered edge.

One of the cuttings aforesaid is primarily, 60 passed between the rollers of a suitable sizing apparatus whereby the unsized surface thereof is preferably given a thin coat of size or other suitable adhesive, it is then laid upon a table or the like with the wet or newly sized surface uppermost, one or more further cuttings, strips or layers of a similar shape but of less dimensions is or are superimposed thereon, the first layer which is 65 preferably dry is laid thereon in contact with the wet or newly sized surface aforesaid, the next and subsequent layers of wadding forming the rest of the filling or stuffing of the pad are superimposed thereon 70 with the wet surface of one layer in contact with the dry surface of another layer in accordance with the thickness and shape of the pad required. The other cutting aforesaid forming a part of the cover is also 75 given a film of size preferably upon the unsized surface thereof and laid with this surface in contact with the dry surface of the uppermost layer of the filling. The aforesaid layers of the desired shape, number and 80 of varying sizes as arranged to form the pad, are taken and passed between pressure rollers, or they may be pressed together by hand or by other suitable means as desired causing the wet size upon each inner layer 85 and upon the upper and lower portions of the cover to more or less penetrate the dry surfaces of the contacting layers sufficient to cause them to adhere together, whilst the overlapping edges of the cover section are 90 also brought into contact with the same effect. Although it is preferable the layers forming the outer cover should be placed with the original dry sized surfaces outside, this position may be reversed, with the 95 said dry sized surfaces after receiving a film of wet or liquid size, inside; in which case the pad after being pressed is passed through the sizing rollers so as to receive a coating of size upon both outer surfaces.

The pad after being pressed as aforesaid, 100 is then dried in any suitable manner or by any suitable means, the size in drying still further cements together the surrounding edges of both sections of the cover which 105 thus completely encloses the other layers with the result that a pad is obtained pos-

sessing all the advantages before-mentioned.

I attain these objects by the means illustrated in the accompanying drawings, in which:—

5 Fig. 1 is a front view of one example of a pad for garments constructed according to this invention, showing in broken lines the relatively different sized layers of cotton wadding forming the filling.

10 Fig. 2 is a side elevation of the different layers of cotton wadding employed in constructing the pad shown at Fig. 1, showing their arrangement relatively to the surfaces newly sized.

15 Fig. 3 is a similar view to Fig. 2, showing the stage of manufacture of the pad just prior to being pressed.

Fig. 4 is a sectional side view through the line 2, 2, of Fig. 1, showing the overlapping edges of the cover sections united after the 20 pressing operation.

Fig. 5 is a cross-section of Fig. 4.

Referring to the drawings which show one construction of pad as an example, A, A, 25 are the outer layers of cotton wadding adapted to form the cover of the pad, B, B, are the surfaces adapted to receive a film of size, C, C, are the dry or originally sized surfaces, D, D, are the inner layers of different sizes.

The relative arrangement of the dry sized and unsized surfaces with the wet or newly sized surfaces of the inner layers may be varied, as desired, but the relative arrangement 30 of the wet sized surfaces of the covering

layers remains constant whereby the meeting edges of their wet surfaces are adapted when brought together to cause them to adhere and unite so as to entirely enclose the inner layers for the purposes aforesaid. If desired, the aforesaid covering layers may similarly enclose layers of unsized wadding. It is also advisable that the film of size or the like liquid applied to said wadding should be so thin as to form a backing therefor without being liable to create a stiffness in any part thereof.

40 It will be observed that this shape of pad is given by way of example only and any other suitable shape or thickness of pad may be built up upon the lines aforesaid. By cutting the pad shown in the drawings transversely into two equal parts the said parts may be adapted to serve as a pair of shoulder pads.

50 What I claim as my invention and desire to secure by Letters Patent, is:—

Pads for garments, comprising a plurality of outer and a plurality of inner layers of fibre wadding, the outer layers being of the same dimension and the inner layers being each of different dimension and each smaller than the outer layers, the inner layers being adhesively secured together and disposed between the outer layers, and the outer layers being adhesively secured together at their edges to confine the inner layers.

60 In testimony whereof I have signed my name to this specification.

ARNOLD GLADSTONE SLADDIN.
